UNITED STATES PATENT OFFICE

2,439,642

ADJUSTABLE HOSE HOLDER

Mayfield C. White, New York, N. Y.

Application July 28, 1945, Serial No. 607,521

2 Claims. (Cl. 248—84)

1

This invention relates to improvements in hose holders and, more specifically, to an adjustable holder for a cooling fluid hose used in connection with a horizontal boring machine tool or the like.

The primary object of the present invention is the provision of a device of the character described which will safely hold a hose in adjusted position and which will prevent any dislodging of the hose due to vibrations or due to a changing pressure of the fluid which passes through the hose;

Another object of the present invention is the provision of a device of the character described which will firmly grasp and hold the hose from four sides and whose lateral pressure upon the hose will increase whenever its pressure from above and below increases, so that the hose cannot be squeezed more or less flat from two opposite sides;

Still another object of the present invention is the provision of a device of the character described which is simple in construction, easy to manipulate, and inexpensive to manufacture, but which is well adapted to withstand the rough usage to which devices of this kind are ordinarily subjected.

Further objects of the instant invention reside in any novel feature of construction or operation or novel combination of parts present in the embodiment of the invention described and shown in the accompanying drawing whether within or without the scope of the appended claims and irrespective of other specific statements as to the scope of the invention contained herein.

In the drawing:

Figure 1 is a side elevation of a preferred embodiment of my invention as it appears when used in connection with a single end horizontal boring machine;

Figure 2 is a vertical cross-sectional view of the device drawn at an enlarged scale;

Figure 3 is a plan view of a detail; and

Figure 4 is a side elevation of the detail of Fig. 3.

Similar numerals refer to similar parts throughout the several views.

In the drawing, the numeral 1 denotes a machine tool table upon which rests a tool support 2 that carries a motor 3 and a revolving tool 4. A sliding table 5, holding the work W, is in a well known manner provided with T-shaped members 6 which engage longitudinal T-slots 7 in the table 1. The parts 1 to 7 inclusive forming no part of my present invention are illustrated in the drawing only for aiding in the description of my invention.

2

A supporting shaft 8, which has a threaded portion 9, extends upwardly from the sliding table 5, and can be vertically adjusted by screwing it more or less deeply into the table 5. A nut 10 allows a retaining of shaft 8 in an adjusted position, and the table 1 is provided with a longitudinal slot 11, so that the lower portion of shaft 8 can be extended below the lower surface of the sliding table 5. The upper portion of shaft 8 is connected to a curved clamp 12 whose extremities are provided with horizontal lugs to which upwardly extending threaded bolts 17 are secured. A second clamp 13, which is of substantially the same shape and size as is clamp 12, is arranged above the clamp 12; and the bolts 17 are extended through the lugs of clamp 13. The clamps 12 and 13 are of considerable width, so that a hose 14 can be held safely between them. In order to make it possible that hoses of different diameters can be held by one and the same clamps 12 and 13, I prefer to make the curved portions of said clamps of a larger radius than is the outer radius of a medium sized hose ordinarily used for the conducting of cooling fluid to the rear of the work W.

Since such oversized clamps grasp the hose 14 only partially, I prefer to provide also for a lateral grip of the hose 14. I prefer to carry out this feature of my invention in the manner shown in Fig. 2, where it will be seen that two wedge members 15 are placed between the clamps 12 and 13 in such a manner that the tapering sides of each wedge member 15 are adjacent the inner side of the corner portions of the clamps 12 and 13, so that the wedges will be forced toward each other when the clamps 12 and 13 are being pressed toward each other by tightening of the screws 17. The wide front portion of each wedge 15 is curved (Figs. 2 and 4), and from the narrow portion of each wedge extends a longitudinal lug which is provided with a slot 16. These wedge lugs are located between the lugs of the clamps 12 and 13, and the bolts 17 are extended through the slots 16.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

Having thus described my invention, what I

claim and desire to secure by Letters Patent in the United States is:

1. In an adjustable hose holder which consists of a pair of curved clamps adapted to hold a hose between them and having lugs at each extremity and of a vertically adjustable supporting shaft connecting one of said clamps to a base, a pair of wedges from whose narrow portions slotted lugs are extended which are located between the lugs of said clamps, and threaded bolts connecting the clamp lugs to each other and extending through said wedge lugs, all substantially as set forth.

2. In an adjustable hose holder which comprises a pair of curved clamps from whose extremities lugs are extended, the combination of a pair of wedges from whose narrow portions slotted lugs are extended which are located between the lugs of said clamps, with threaded bolts connecting the clamp lugs to each other and

10

extending through said wedge lugs, and a vertically adjustable supporting shaft connecting one of said clamps to a horizontally shiftable base plate, said wedges being arranged between said clamps in such a manner that their tapering sides are adjacent the inner sides of said clamps so that the wedges will be forced toward each other when the clamps are being pressed toward each other, all substantially as described.

MAYFIELD C. WHITE.
